NOZZLE FOR AN EAR SYRINGE OR THE LIKE

Roy Algot Anderson, 4554 N. Malden Ave., Chicago, Ill.

Filed Sept. 7, 1960, Ser. No. 62,056

Term of patent 14 years

(Cl. D83—1)

Fig. 1

Fig. 2

Fig. 3

Fig. 4

FIG. 1 is a side elevational view of a nozzle for an ear syringe or the like embodying my new design;

FIG. 2 is a top plan view thereof;

FIG. 3 is a front elevational view thereof; and

FIG. 4 is a vertical sectional view thereof taken on line 4-4 of FIG. 2.

The dominant features of my design reside in the full-line portions of the drawing.

I claim:

The ornamental design for a nozzle for an ear syringe or the like, as shown and described.
